W. M. BAUMHECKEL

CLOSURE ATTACHMENT FOR RECEPTACLES

Filed June 26, 1924

UNITED STATES PATENT OFFICE.

WILLIAM M. BAUMHECKEL, OF MILWAUKEE, WISCONSIN, ASSIGNOR OF ONE-HALF TO
LOUIS C. SCHARNHORST, OF MILWAUKEE, WISCONSIN.

CLOSURE ATTACHMENT FOR RECEPTACLES.

Application filed June 26, 1924. Serial No. 722,507.

This invention relates in general to devices, such as closures or mountings therefore, intended for use on receptacles and the like, which are adapted for permanent or 5 semi-permanent attachment in operative position; and the invention relates more particularly to such devices as are primarily intended for use with receptacles of automobiles, where the closure or the like is of such 10 ornamental design or serves as a mounting for an instrument of such value that it is desirable that the device be associated with the automobile radiator or other receptacle in such a manner as to frustrate unauthorized 15 attempts at removal of the device.

It is desirable to provide certain receptacles, such as the radiator of an automobile, with a closure of a more or less pleasing or ornamental design, in some cases, this 20 closure having additional utility as a mounting for a device for giving a desired indication, as of the level or temperature or other characteristic of the cooling fluid in the radiator or other part of the cooling system 25 of the engine. And, especially for the reason that the closure may have considerable intrinsic value on account of its ornamental design, and the further value of the indicating device carried by the closure, it 30 is highly desirable that the design and construction of the closure be such as to prevent at least any ordinary attempts at unauthorized removal of the closure, while permitting any desired degree of accessibility 35 to the radiator for ordinary purposes, as for replenishing the cooling fluid therein, or for such extraordinary purposes as include 40 repairs to the radiator or replacement of the closure.

Due to the fact that different types and sizes of receptacles, as for instance automobile radiators, are provided with orifices or openings, usually through tubular spouts of different sizes and shapes, it is particularly 45 desirable that a closure for such a receptacle be universal to the extent that a single size or design of closure be adapted to fit and be used upon the several different sizes and shapes of apertures or spouts 50 of the radiators or other receptacles.

The present invention contemplates a device of utility as a closure for receptacles,

such as automobile radiators, which is of such design as to be universal to the extent of being adapted to fit a number of different sizes and styles of receptacle openings, and is capable of being readily secured in operative position on a receptacle in such a manner as to permit the desired degree of accessibility to the interior of the receptacle 65 while preventing unauthorized removal of the closure from the receptacle.

It is an object of the present invention to provide a device of the character described 65 which is of improved design and construction and which is capable of maintaining itself in operative position on a receptacle or other article while permitting any desired degree of communication with the receptacle or article with which the device is associated. 70

It is a further object of this invention to provide a receptacle closure of improved design and construction which is extremely 75 simple and efficient and is universal as to the feature of being adapted to be operatively associated with receptacle openings or spouts of different sizes and styles, and which may be readily attached in operative position on a receptacle in such a manner as to defeat 80 attempts at unauthorized removal of the closure while permitting desired access to the interior of the receptacle.

It is a further object of the present invention to provide a receptacle closure of 85 the character described which is of extremely simple design and construction and is adapted to serve as a combined closure of more or less ornamental design for an automobile radiator and a mounting for an indicating device. 90

These and other objects and advantages are attained by the present invention, various novel features and advantages of which will be apparent from the description and 95 drawing disclosing one embodiment of the invention, and will be more particularly pointed out in the claims.

In the drawings:

Fig. 1 is a front elevation, partly in section, of a receptacle closure embodying features of the present invention, the section being along the lines I—I of Figs. 3 and 4. 100

Fig. 2 is a sectional view along the line

II-II of Fig. 1 with the indicating device removed.

Fig. 3 is a sectional view along the line III-III of Fig. 1, showing the underneath 5 side of the closure.

Fig. 4 is a plan view with the main portion of the closure cover broken off.

Fig. 5 is an enlarged fragmental plan view similar to Fig. 4, showing a modification 10 of a detail of construction and design.

Fig. 6 is a fragmental view along the line VI-VI of Fig. 5.

In the embodiment of the invention illustrated in the drawings, the receptacle 1 may 15 be considered as the radiator of an automobile, the radiator being provided with a filling orifice in the form of a tubular spout 2, ordinarily, though not necessarily, of circular outline. A closure embodying 20 features of the present invention is indicated at 3 and comprises an outer annular or cylindrical wall 4 disposed outside of the upper end of the spout 2, with an inner flange or shelf-like diaphragm 5 having at its inner periphery a plurality of spaced, preferably 25 integral, and downwardly extending arms 6, the recesses or spaces between the arms being indicated at 7. An annular disk or hub portion 8 is carried by, being preferably integrally united with, the spaced arms 6 and 30 is provided with a central or axial threaded bore 9. As indicated, the hub 8 has radially extending portions 6^a in alignment and integral with the arms 6, the arrangement 35 being such that the recesses 7 or continuations thereof in the hub portion are of substantial extent.

A plurality of pins 10, preferably of hardened steel or bronze are slidable in 40 radial apertures 11, through the portions 6^a of the hub 8, the pins extending beyond the inner and outer walls of the hub portion and having pointed outer ends and rounded or cam-shaped inner ends, as indicated. A 45 screw-plug 12 having a cone-shaped lower end 13 is threaded in the bore 9, the relation of the parts being such that as the cone-shaped lower end 13 is forced into engagement with the inner rounded ends of the 50 pins 10, the latter are forced outwardly in the apertures 11. The apertures 11 preferably have their axes so inclined to the axis of the bore 9 that when the closure 3 is in 55 operative position upon a receptacle, with the axis of the bore and screw plug substantially vertical, the pins are sufficiently inclined from the horizontal that the action of gravity causes the pins to be retracted partially within the bore of the hub. With the 60 surfaces of the walls of apertures 11 and the pins 10 suitably finished, little inclination of the axes of the apertures 11 is needed to secure the desired retraction of the pins.

A flexible gasket 14 is disposed in position 65 against the lower side of the shelf or

diaphragm 5 within the annular space formed between the cylindrical wall 4 and the spaced arms 6. The normal operative position of the closure is as shown in the drawings, with the upper edge of the spout 70 2 in firm fluid-tight engagement with the under side of the gasket 14.

A cover 15 is provided for the receptacle, the same being generally dome-shaped, with an outer edge or lip bearing upon a gasket 75 16 disposed on the upper side of the diaphragm or flange 5 within an upwardly extending portion of the cylindrical wall 4, as indicated. The upper wall of the cover is provided with an aperture 17 adapted to 80 receive the threaded shank or stem 18 of an indicating device, a nut 19 threaded on the stem 17 and bearing against the lower side of the upper wall of the cover serving to 85 secure the indicating device in operative position thereon, as indicated.

The cover 15 is cut away at its periphery to form a projection 23 adapted to lie between spaced projections 24 at the upper side of the cylindrical wall 4, the projection 23 and projections 24 having aligned apertures adapted to receive a hinge pin 25, the aperture on one of the projections 24 preferably having a closed end and the pin preferably being driven in flush with the outer wall of the other projection 24, so as to frustrate any ordinary attempt at removal of the hinge pin and consequent removal of the pivoted cover 15 and the indicating 95 device carried thereby.

The cylindrical wall 4 of the closure is provided with an elongated projection 26 at a point diametrically opposite the hinged projection 23, the projection 26 being apertured to pivotally receive a portion of a bail 27 which is adapted to be swung upwardly to the position indicated in Figs. 1 and 2, wherein it engages with the upper side of a nose or projection 28 on the cover 15, to thereby hold the cover and the indicating device carried thereby securely in operative position, with the cover in fluid-tight engagement with the gasket 16.

In assembling the closure 3 in operative position on the spout 2, it being assumed that the indicating device is mounted on the cover 15, although the indicating device may be mounted on the cover at any time after the closure is in place on the spout, the closure is placed upon the spout so that the upper end of the spout lies in the recess between the cylindrical wall 4 and the spaced arms 6, the upper end of the spout bearing against the gasket 14. During this operation of placing the closure on the spout, the pins 10 are in retracted position so as to permit insertion of the hub portion 8 and the arms 6 within the spout. By means of a socket wrench or other tool which may be inserted in a polygonal socket 31 at the 115 120 125 130

upper side of the screw plug 12, when the cover is swung back to open position, the plug is threaded into the bore 9 of the hub so that the lower cone-shaped end 13 of the 5 plug bears against the inner rounded ends of the pins 10, forcing the same outwardly and upwardly to a slight extent, depending upon the upward inclination of the guiding apertures 12. With the pins 10 all of the 10 same length in the case of a spout of circular cross-sectional shape, or any suitable length depending upon the shape or outline of the spout, the effect of the initial engagement of the pins with the wall of the spout is to center the closure upon the spout. Further operation of the screw plug 12 and the pins 10, preferably with the closure forcibly held on the spout, causes the pins to be forced into secure holding engagement with 15 the wall of the spout, the hardened steel pins actually entering and firmly gripping the wall of the spout and thereby forcing the upper edge of the spout upwardly into firm engagement with the gasket 14 and holding 20 25 and securing the closure in operative position on the spout with the gasket 14 forming a fluid-tight seal for the upper end of the spout.

After the closure has been secured in operative position as described, the recess 31 may be filled with a fusible metal or other filling which hardens and thus prevents insertion of the operating tool to operative position for the purpose of removing the 30 closure.

It is preferable to provide additional means for frustrating unauthorized attempts at removal of the plug 12. As a means to this end, the portion of the plug 12 40 rounding the polygonal recess 31, this portion constituting a wall 32, may be provided with one or more radial recesses 33 communicating at their inner ends with the recess 31 and, when the plug is suitably positioned, communicating with one or more corresponding recesses 34 in the wall of the apertured hub 8. When the plug is finally adjusted to a position wherein the recesses 33 of the plug and recesses 34 of the hub 50 communicate, as shown in Figs. 2 and 4, the fusible filling enters these recesses, these projecting portions of the filling constituting, when the filling hardens, a means for positively locking the plug against rotation. 55 The provision of these locking projections of the filling material may be insured independently of the final position of adjustment of the plug 12, through the further provision of an annular recess 35 at the periphery of the plug and a corresponding annular recess 36 about the wall of the bore 9 of the hub 8, the fusible metal or other filling being adapted to occupy such annular recesses and the communicating radial recesses 33 and 34, so as to lock the plug 60 65

against rotation in either direction. In Fig. 2, the fusible filling material has not yet been applied, while in Fig. 4, this filling material 37 is indicated as having been applied. 70

In Figs. 2 and 4, the plug 12 and the hub 8 are shown as provided with one pair of recesses 33 and 34, respectively; whereas in Figs. 5 and 6, both the hub 8 and the wall 32 are shown as provided with six radial recesses which, in combination with the annular recesses 35 and 36 in the plug 12 and the hub 8, respectively, serve to lock the plug against rotation independently of the final adjusted position of the same. 75 80

Under ordinary circumstances, the closure 3 and the mounting for the indicating device are removable from the radiator only by destruction of the spout or a portion of the closure, for the pins 10 are securely held within the metal of the spout through the holding action of the screw plug 12, the latter being locked in finally adjusted position and there being no ordinary means for applying a tool to the screw plug so as 85 to actuate the same. The simplest ordinary method of removal of the closure from the spout, and, for that matter, necessary only in rare instances, includes the removal of the radiator from the automobile frame and engine connections, the radiator being afterward inverted and suitable heat, ordinarily in the form of a blow-torch, being applied to the fusible metal or other filling in the socket 31 and the recesses 33, 34, 35 and 36, 90 95 100 the filling, when heated to the required degree, falling out of the several recesses in the plug and the hub 8. After removal of the fusible filling, it will be apparent that the plug 12 can readily be threaded outwardly to a position wherein the locking pins 10 readily drop out of holding engagement with the spout, thus permitting withdrawal of the hub portion 8 and the arms 6 from within the spout. 105 110

The indicating device mounted on the cover of the closure may be of any suitable type for indicating the temperature, fluid-level or pressure within the radiator or, in fact, any desired condition in the radiator or other part of the engine unit, the specific indicating device here shown being of the temperature-indicating type wherein the heat-responsive portion is located either wholly within the dome-shaped cap or partly within the central recesses formed between the spaced arms 6. It will be apparent, however, that the downwardly extending portion of the indicating device may readily be of such form as to pass through the space 7 between adjacent arms 6 and downwardly to any desired extent into the spout or the body portion of the radiator. 115 120 125

In replenishing the cooling liquid in the radiator, the cover 15 is swung backward on 130

its hinge, after removal of the bail 26, and cooling fluid may then be poured into the receptacle through the openings or spaces 7 between the arms 6 and the spout 2.

5. Because of the fact that no threaded or similar close fitting connection of the closure to the receptacle is required, the closure may readily be universal as to the feature of its capability of fitting spouts or openings in 10 radiators or receptacles of sizes which vary practically all the way between the outer diameter of the arms 6 and the inner diameter of the cylindrical portion or sleeve 4 of the closure. Thus, with a stock of only one or, 15 possibly, two sizes of closures embodying the present invention, a suitable closure which lends itself readily to any desired ornamentation or special design, as for instance, the provision of the side bars shown, may 20 be provided for any of the ordinary types or makes of automobile radiators at present on the market, and, in fact, many other receptacles of common and ordinary use.

While the invention has been more particularly described in connection with its utility or application to closures for automobile radiators or the like, it will be apparent that as to one or more or all of its features or elements, the invention is capable of and readily adapted for utility in other applications and relationships where its inherent features are desired, and as to such other applications and relationships, the embodiment shown in the drawings and 35 more particularly described herein is intended to be only illustrative and not limitative.

And it should be understood generally that the invention claimed hereinbelow is 40 not to be considered limited to the specific features of design and construction shown and described herein, for obvious modifications will be apparent to those skilled in the art.

45. It is claimed and desired to secure by Letters Patent:

1. An attachment for the tubular spout of a receptacle of the character of an automobile radiator, comprising in combination, 50 a seating portion adapted to make fluid-tight engagement with the open edge of said spout, and an apertured portion united to said seating portion and adapted to enter within the spout of the receptacle, and a 55 plurality of adjustable, angularly spaced gripping members carried by said entering portion, and an actuating device carried by and substantially co-axial with said entering portion and adapted to force said gripping members into holding engagement with the side wall of said spout, said apertured portion when in operative position on said spout permitting the discharge of fluid therethrough to said receptacle.

60. 2. An attachment of the class described

for apertured articles, comprising in combination, an apertured body portion having an annular part adapted to make fluid-tight engagement with a cooperative portion of the wall of a receptacle, and means for securing said body portion in operative position on said receptacle, said securing means comprising a plurality of angularly displaced and spaced gripping elements carried by and movable relative to said body portion, and an adjustable member carried by said body portion and adapted to actuate said gripping elements into gripping relation with the wall of the receptacle, said apertured portion when in operative position on said receptacle permitting the discharge of fluid therethrough to said receptacle, said member being provided with facilities for cooperation with a device for preventing unauthorized release of said gripping elements.

3. An attachment of the class described for apertured articles, comprising in combination, an apertured body portion having an annular part adapted to make fluid-tight engagement with a cooperative portion of the wall of a receptacle, and means for securing said body portion in operative position on said receptacle, said securing means comprising a plurality of angularly spaced elements adapted to be forced into holding relation with the wall of the article about the aperture therein, and an adjustable member cooperative with said holding elements for actuating said holding elements into holding position, said adjustable member presenting a recess adapted to receive an element capable of functioning to prevent unauthorized release of said holding elements.

4. An attachment of the class described for apertured receptacles of the character of an automobile radiator, comprising in combination, an element having a seating portion cooperative with an open end of a tubular extension of a receptacle, and a portion adapted to enter said tubular extension, and means adapted to secure said element in operative position on the said tubular extension, said means comprising a gripping member adjustable into position wherein it is adapted to forcibly grip the side wall of said tubular extension, said portion of said element within said tubular extension permitting the discharge of fluid therethrough to said receptacle, and a removable cover for said element.

5. An attachment of the class described for apertured receptacles of the character of an automobile radiator, comprising in combination, an element having a seating portion cooperating with an open end of a tubular extension of a receptacle, and a portion adapted to enter within said tubular extension, and means adapted to secure said

- element in operative position on said tubular extension of the receptacle, said means comprising a plurality of angularly spaced gripping members, and actuating means therefor carried by said entering portion and adapted to cause said gripping members to forcibly grip the inner wall of the tubular extension of the receptacle, said portion of said element within said tubular extension permitting the discharge of fluid therethrough to said receptacle, and a removable cover for said element.
6. An attachment for apertured receptacles of the character of an automobile radiator having a tubular spout or nipple about the aperture, comprising in combination, a seating portion adapted to cooperate with the open end of a radiator nipple, a portion extending at an angle from said seating portion, and means associated with said extending portion and operative to grip the side wall of said nipple and thereby secure said attachment to a plurality of sizes of nipples with said seating portion in fluid-tight engagement with the end of the nipple, said attachment when in operative position on said radiator permitting filling said radiator through said attachment.
7. An attachment for apertured receptacles of the character of an automobile radiator having a tubular spout or nipple about the aperture, comprising in combination, a seating portion adapted to cooperate with the open end of a radiator nipple, a portion extending at an angle from said seating portion, and means associated with said extending portion and operative to secure said attachment to a plurality of sizes of nipples with said seating portion in fluid-tight engagement with the end of the nipple, said means comprising a plurality of spaced gripping elements carried by said extending portion and adapted to be forced and held in gripping relation with the side wall of the nipple, said attachment when in operative position on said radiator permitting filling said radiator through said attachment.
8. An attachment for apertured receptacles of the character of an automobile radiator having a tubular spout or nipple about the aperture, comprising in combination, a seating portion adapted to cooperate with the open end of a radiator nipple, a portion extending at an angle from said seating portion, and means associated with said extending portion and operative to secure said attachment to a plurality of sizes of nipples with said seating portion in fluid-tight engagement with the end of the nipple, said means comprising a plurality of spaced, radially extending gripping elements carried by said extending portion, and an axially disposed actuating element operative to force said gripping elements into holding engagement with the wall of the nipple, said actuating element having a recessed portion adapted to receive means for preventing unauthorized release of said gripping elements.
9. An attachment for apertured receptacles of the character of an automobile radiator having a tubular spout or nipple about the aperture, comprising in combination, a seating portion adapted to cooperate with the open end of a radiator nipple, an apertured portion extending at an angle from said seating portion and adapted to enter the nipple, said entering portion being apertured to permit fluid passage therethrough, and gripping means carried by said entering portion and adapted to secure said attachment in operative position on a plurality of sizes of nipples through forcible engagement of the side wall of the nipple by said gripping means, and a removable cover for said attachment, said cover being adapted to serve as a mounting for an indicating device.
10. An attachment for apertured receptacles of the character of an automobile radiator having a tubular spout or nipple about the aperture, comprising in combination, a seating portion adapted to cooperate with the open end of a radiator nipple, a peripheral portion extending at an angle from said seating portion, and an apertured inner portion extending in the same general direction from said seating portion, the space between said two extending portions being adapted to receive a gasket and a plurality of sizes of nipples, and a plurality of gripping elements carried by said inner extending portion and adapted to be forced in gripping engagement with the inner side wall of the nipple to maintain the attachment in operative position on any of said sizes of nipples.
11. In combination with a receptacle of the character of an automobile radiator, having a tubular spout or nipple, a closure attachment comprising in combination, a seating portion cooperative with said spout, a portion depending from said seating portion, said depending portion and said tubular spout being telescopically disposed one within the other, a portion of said attachment within said spout being apertured to permit filling said receptacle therethrough, means operatively associated with said depending portion for gripping the side wall of said spout, and means cooperative with said gripping means for holding the latter in gripping position whereby said closure attachment is held in operative position on said spout.
12. In combination with a receptacle of the character of an automobile radiator having a tubular spout or nipple, a closure attachment comprising in combination, an apertured portion provided with an annular seat cooperative with said spout, a portion depending from said seating portion, said de-

- 5 pending portion and said tubular spout being telescopically disposed one within the other, a plurality of spaced gripping elements operatively associated with said depending portion, and means for forcing and holding said gripping elements in gripping relation with the side wall of said spout whereby said closure attachment is forced into and held in operative position on said 10 spout.
13. In combination with a receptacle of the character of an automobile radiator having a tubular spout or nipple, a closure attachment comprising in combination, a seating portion cooperative with said spout, a portion depending from said seating portion, said depending portion and said tubular spout being telescopically disposed one within the other, a portion of said attachment 15 within said spout being apertured to permit filling said receptacle therethrough, a plurality of spaced gripping elements operatively associated with said depending portion, and instrumentalities cooperative with 20 said gripping elements and said depending portion for forcing said gripping elements into gripping relation with the side wall of said spout and for holding said closure attachment in operative position against unauthorized removal.
14. In combination with a receptacle of the character of an automobile radiator having a tubular spout or nipple, a closure attachment comprising in combination, a seating portion cooperative with said spout, an apertured portion depending from said seating portion, said depending portion and said tubular spout being telescopically disposed one within the other, a portion of said attachment within said spout being apertured 25 to permit filling said receptacle therethrough, means operatively associated with said depending portion for gripping the side wall of said spout and forcing the latter into engagement with said seating portion to secure said closure attachment in operative position on said spout, and means for holding said gripping means in operative position against unauthorized release.
15. In combination with a receptacle of the character of an automobile radiator having a tubular spout or nipple, a closure attachment comprising in combination, a seating portion cooperative with said spout, an apertured portion associated with said seating portion and disposed within said spout 30 permitting filling said receptacle therethrough when said attachment is in operative position on said spout, spaced adjustable gripping elements carried by said apertured portion and guided to move in substantially straight paths, and an adjustable actuating element carried by said apertured portion and operative to force and hold said gripping elements into gripping relation with 35 the side wall of said spout for the purpose of securing said closure attachment in operative position on said spout.
16. In combination with a receptacle of the character of an automobile radiator having a tubular spout or nipple, a closure attachment comprising in combination, a seating portion cooperative with said spout, a portion depending from said seating portion and disposed within said spout, said depending portion comprising a plurality of spaced arms and permitting fluid communication through said spout with the interior of said receptacle, spaced gripping elements carried by said depending portion and in substantial alinement with said depending arms, said gripping elements being adjustable in a direction having an upward component, and means carried by said depending portion for actuating said gripping elements into position wherein they forcibly grip the wall of said spout and cause said seating portion to be drawn toward said spout.
17. In combination with a receptacle of the character of an automobile radiator having a tubular spout or nipple, a closure attachment comprising in combination, a seating portion cooperative with said spout, a portion depending from said seating portion and disposed within said spout, spaced adjustable gripping elements carried by said depending portion, and an adjustable actuating element carried by said depending portion and operative to force and hold said gripping elements into gripping relation with the wall of said spout for the purpose of securing said closure attachment in operative position on said spout, said actuating element and said depending portion having cooperative recessed portions, and a fusible element disposed in said cooperative recesses and adapted to lock said actuating element and said gripping elements in operative position.
18. In combination with a receptacle of the character of an automobile radiator having a tubular spout or nipple, a closure attachment comprising in combination, a seating portion cooperative with said spout, an apertured portion depending from said seating portion and disposed within said spout, spaced adjustable gripping elements carried by said depending portion, and an adjustable actuating element carried by said depending portion and operative to force and hold said gripping elements into gripping relation with the wall of said spout for the purpose of securing said closure attachment in operative position on said spout, said actuating element having a recessed portion, and a gravity releasable means cooperative with said recessed portion of said actuating element for holding said actuating element against unauthorized release.
19. An attachment for apertured recep-

tacles of the character of an automobile radiator having a tubular spout or nipple about the aperture, comprising in combination, a seating portion adapted to cooperate with the open end of a radiator nipple, a portion extending at an angle from said seating portion, and means associated with said extending portion and operative to secure said attachment to a plurality of sizes

of nipples with said seating portion in fluid-tight engagement with the end of the nipple, said securing means comprising a gripping device, and means for forcing said gripping device into the material of the side wall of said nipple.

In witness whereof I affix my signature hereto.

WILLIAM M. BAUMHECKEL.
